UNITED STATES PATENT OFFICE.

EDWARD E. LAWRENCE, OF JAMAICA, NEW YORK, ASSIGNOR TO LOOSE-WILES BISCUIT COMPANY, OF LONG ISLAND CITY, NEW YORK, A CORPORATION OF NEW YORK.

RECEPTACLE FILLING AND CLOSING APPARATUS.

1,365,415.

Specification of Letters Patent. Patented Jan. 11, 1921.

Application filed June 15, 1916. Serial No. 103,875.

To all whom it may concern:

Be it known that I, EDWARD E. LAWRENCE, a citizen of the United States, and a resident of Jamaica, in the county of Queens 5 and State of New York, have invented an Improvement in Receptacle Filling and Closing Apparatus, of which the following description, in connection with the accompanying drawings, is a specification, like 10 characters on the drawings representing like parts.

This invention relates to receptacle filling and closing apparatus, and particularly to apparatus for filling cartons with oyster 15 crackers and for closing said cartons.

In order that the principle of the invention may be readily understood, I have disclosed a single embodiment thereof in the accompanying drawings, wherein—

20 Figure 1 is a right hand side elevation, partially in section, of one form of apparatus embodying my invention;

Fig. 2 is a top plan view of the apparatus shown in Fig. 1;

25 Fig. 3 is a left hand side elevation, partially in section, of said apparatus;

Fig. 4 is an elevation from the discharge end of said apparatus, the discharge chute being omitted and the filling troughs being 30 in section;

Fig. 5 is a horizontal, longitudinal section of the apparatus taken just above the troughs for the sprocket belt conveyors upon the line 5—5 of Fig. 1;

35 Fig. 6 is a view, partially in transverse section upon the line 6—6 of Fig. 5 and partially in end elevation looking from the feeding in end of the machine;

Fig. 7 is a right hand side elevation of 40 the apparatus, partially in longitudinal section, upon the line 7—7 of Fig. 5;

Fig. 8 is a detail in top plan view upon an enlarged scale of the end flap folding members and the member for folding the 45 upstanding front wall of the lining;

Fig. 9 is a view of the same parts differently positioned;

Fig. 10 is a view in vertical section of 50 the carton closing devices and certain of the operating parts therefor;

Fig. 11 is a view of the same parts differently positioned;

Fig. 12 is a plan view upon an enlarged scale of certain of the carton closing devices;

Fig. 13 is a vertical section upon the line 13—13 of Fig. 12;

Fig. 14 is a view similar to Fig. 12 of the parts differently positioned;

Fig. 15 is a vertical section upon the line 15—15 of Fig. 14;

Fig. 16 is a view similar to Fig. 12 but with the parts differently positioned;

Fig. 17 is a vertical section upon the line 17—17 of Fig. 16;

Fig. 18 is a view similar to Fig. 16, but with the parts differently positioned;

Fig. 19 is a vertical section upon the line 19—19 of Fig. 18;

Fig. 20 is a vertical section upon the line 20—20 of Fig. 18;

Fig. 21 is a view in vertical section disclosing the means for depositing the crackers in the carton;

Fig. 22 is a transverse section upon the line 22—22 of Fig. 21;

Fig. 23 is a vertical longitudinal section upon the line 23—23 of Fig. 21;

Figs. 24, 25 and 26 are perspective views, partially in section, illustrating certain steps 80 in the closing of the carton;

Fig. 27 is a transverse section taken through the actuating means for the member that folds the upstanding front wall of the lining;

Fig. 28 is a detail in longitudinal section showing a portion of said actuating means; and

Fig. 29 is a plan view of the blank from 90 which the carton is formed.

While the apparatus herein disclosed may be used in other relations, it is particularly intended for use in filling paste-board cartons with oyster crackers and thereafter closing the carton by infolding the upstanding flaps or cover portions thereof. In the disclosed embodiment of my invention, the crackers are deposited in any suitable manner upon a traveling support and are thereby deposited in a series of pockets formed in or carried by a rotating member. The disclosed embodiment of my invention is of a duplex apparatus, and in accordance with such disclosure the crackers are discharged prefer-

55

65

85

90

95

100

ably simultaneously from said pockets at opposite sides of the machine into cartons which are fed by conveyers into position beneath the discharging pockets. After filling, the upstanding flap or cover portions of the cartons are folded down and the cartons are then discharged from the apparatus. My invention is in no wise limited to the disclosure herein made, as it is evident that 10 many changes can be made within the scope and purpose of my invention. Referring more particularly to the drawings, the framing is herein represented as consisting of a series of uprights 1 at opposite sides, and at 15 the ends of the machine are transverse cross or tie members 2, most clearly represented in Fig. 5.

The crackers or other articles with which the receptacles are to be filled are deposited 20 by hand or otherwise in a hopper 3 at the feeding-in end of the machine. The bottom of said hopper is composed of an open mesh, endless apron 4, preferably formed of wire and mounted for movement in the direction 25 of the arrow in Fig. 7, upon rolls 5, 6 supported in the framing of the machine and continuously driven as hereinafter described. Preferably by the rolls 5, 6 the crackers or other articles are fed upwardly and the 30 crumbs are discharged through the meshes of the belt onto a transverse sheathing 7 here shown as flat and which may, if desired, as shown in Fig. 7, extend from front to rear of the machine as well as from side to side 35 thereof. If desired the rear portion of said sheathing 7 may be downwardly inclined toward the feeding-in end of the machine throughout the extent thereof, that is, vertically beneath said feeding-in apron 4, where- 40 by the crumbs falling through said apron accumulate at the lowest portion of said sheathing for ready removal.

The crackers are delivered from the apron 4 and are deposited through any suitable distributing device. For that purpose I have herein represented a disk-like member 8 mounted upon a vertical pivot and having a series of pockets 9 into which the crackers are deposited in the rotation of said disk-like 50 member. One or more operatives stand at the feeding-in end of the machine and keep a sufficient supply of crackers upon the apron 4, thus insuring the filling of all the pockets 9. In order to prevent overfilling of the 55 pockets and the proper distribution of the crackers, I preferably provide two brushes 10, 11 shown most clearly in Fig. 4. The brush 10 is a stationary one and is positioned transversely of the disk-like member 8 sub- 60 stantially midway from front to rear thereof and at one side of the longitudinal center of the machine for the purpose of preventing the crackers from accidentally getting from the feeding end of the machine into the filling pockets after the pockets have been prop-

erly filled and prior to the discharge thereof. Preferably I employ such a device, inasmuch as in the disclosed embodiment of my invention, certain of the pockets are not discharged until the disk 8 has turned at least 70 through 180° of rotation subsequent to the filling thereof. The said member is rotated in a clockwise direction in Fig. 2, and it will therefore be observed that each pocket after 75 filling passes first under the rotary brush 11. This brush is turned in a clockwise direction and brushes back surplus crackers from the filled pockets toward the filling apron 4. As will be more fully pointed out hereinafter, alternate pockets are discharged in proximity 80 to the rotary brush 11, but the remaining pockets are not discharged until in the vicinity of the stationary brush 10, and there is danger that the last mentioned pockets may accidentally receive an oversupply of 85 crackers if the stationary brush 10 or some other suitable means be not provided for that purpose.

The disk-like member 8 is mounted for rotation in a horizontal plane upon a vertical shaft 12 which, as shown most clearly in Fig. 5, has fast upon the lower end thereof a gear 13 meshing with the worm 14 upon a belt driving shaft 15 hereinafter described. The said disk-like member 8 is thereby given 90 a step-by-step movement of rotation in a clockwise direction, viewing Fig. 2. Inasmuch as the apparatus of the disclosed embodiment of the invention is a duplex one, I have provided two beveled chutes 16, 17, 95 shown most clearly in Figs. 4 and 6, the discharge chute 16 being shown in detail and on an enlarged scale in Fig. 21. Each of said discharge chutes is suitably supported by the framing, as illustrated in Fig. 21, and extends at its upper end beneath the discharging 100 position of the pockets. Each of said pockets is provided with a hinged closure 18 normally held in closed position by a spring 19.

As shown most clearly in Figs. 4 and 6, alternate closures 18 are provided with upwardly and outwardly extending, generally L-shaped lugs 20, the remaining closures being provided with outwardly extending or 115 straight lugs 21. Thus, the two sets of lugs 20, 21 terminate in different horizontal planes, where they are provided with terminal rolls 22, 23. The rolls 22 are adapted to engage the lower curved faces 24 of cam-like brackets 25 having bases 26 supported upon the frame at 27 and shown most clearly in Fig. 21. The remaining or alternate rolls 23, being positioned at a lower level, are not acted upon by the cam-like brackets 25, and hence are not opened at the left-hand side of the machine, viewing Figs. 4 and 6. At the right hand side of the machine I position a corresponding cam-like bracket at a lower level and along the cam-like surface of 120 125 130

which the rolls 23 ride, thereby opening the alternate or remaining closures 18 at the said right-hand side of the machine.

As indicated most clearly in Figs. 2 and 5 21, each of the cam-like brackets for operating the closures 18 is adjustable in and out of operative position, whereby without stopping the mechanism or any part thereof, the disk-like member 8 may be rotated without 10 discharging the contents of the pockets. While this may be effected in any suitable manner, I have herein represented a hand lever 28 located adjacent each of said cam-like brackets, the same being pivoted at 29 15 upon the machine frame and having inwardly extending arms 30 provided with pins adapted to enter slots 31, whereby the bases 26 may be slid in or out when the wing nuts 32 have been loosened. Upon adjustment of the said cam-like brackets into or 20 out of operative position, the wing nuts are again tightened.

At their lower, outer ends, the discharge chutes 16, 17 are provided with any suitable 25 closure means, as shown most clearly in Figs. 21 and 22, and each has two sets of intermeshing fingers 33, 34 respectively pivoted at 35, 36, as indicated in Fig. 6. The sets of fingers 34 are normally held in closed 30 position by the action of a coil spring 37 connected to the pivotal support for the set of fingers 34 and to the exterior of the chute 16, 17 as indicated at 38, and the set of fingers 33 are held in their open or closed position 35 by the finger operating means herein-after described.

The cartons for the oyster crackers or other articles may be of any suitable shape and structure, but I have found the form of car- 40 ton best illustrated in Figs. 24, 25 and 26, and the blank which is shown in Fig. 29 to be well suited to my purpose. The blank which is formed of a single piece is folded into position so as to have two upstanding 45 end flaps 39, 40 and a longitudinally extending cover member 41. Preferably the carton is provided with a separate lining of wax paper or other suitable material and, as indicated in Figs. 24 to 26, the lining has up- 50 wardly extending end portions 42, back portion 43 and front portion 44. The back portion 43 when in upright position extends in parallelism with and flatwise against the cover 41, and the end portions 42 occupy a 55 similar relation with respect to the end flaps 39, 40. The front upstanding portion of the lining, however, extends above the front wall of the carton and as hereinafter described is the first portion of the entire carton to be 60 turned into closed position.

The cartons in open position and with the closure members thereof upstanding as indicated in Fig. 24, are placed transversely upon the two conveyer belts 45, 46, shown 65 most clearly in plan view in Fig. 5. These

belts are horizontally supported by laterally extending portions 47, 48 of the frame and may extend preferably outwardly for a considerable distance. They are represented as broken away in Figs. 2 and 5 to save space. 70 These belts are supported at their outer ends by guide pulleys, not herein shown, and at their inner ends they are supported upon pulleys indicated in dotted lines at 49, 50 in Fig. 5, and in full lines 49, 50 in Fig. 6. 75 Thus, it will be seen that the inner ends of the set of belts are brought into close proximity. The said pulleys 49, 50 are respectively mounted upon shafts 51, 52 suitably mounted in bearings 53—53, 54—54 in cross 80 members of the frame and are provided with gears 55, 56 meshing with each other so that the two belts are driven in opposite directions in unison. As hereinafter described, gear 56 is loosely mounted upon the shaft 52 85 and is adapted periodically to be clutched thereto.

As will be hereinafter described, the said belts are driven intermittently, and it is merely necessary for the attendant or attendants to keep a sufficient supply of open cartons upon the belts 45, 46 to insure the inward feeding of the said cartons at the two sides of the machine. As shown most clearly in Fig. 6, between the upper and 90 lower runs of the belts 45, 46 are interposed supporting or guide members 57, 58, and I have herein represented guide rolls 59, 59, 60, 60 at the inner ends of said members 57, 58. The pulleys 49, 50 are supported at a 100 lower level than the carton-receiving portions of the belts 45, 46, and hence said belts extend at a downward inclination from the guides 59, 60 to said pulleys. I have indicated at 61 in Fig. 6 a guiding roller beneath which the belt 46 extends. As clearly indicated in said Fig. 6, the said belts 45, 46 extend quite abruptly at a downward inclination beneath troughs 62, 63 positioned at 105 right angles to the path of movement of the 110 belts 45, 46. As shown in Fig. 5, at opposite sides of the belts 45, 46, I position longitudinally extending guide plates 64—64, 65—65, the inner ends of which extend directly into the troughs 62, 63, so as to guide 115 and support the incoming cartons directly into the said troughs 62, 63.

The said troughs are positioned at opposite sides of the machine and directly beneath the discharge end of the chutes 16, 17, 120 so that when the cartons have been received in the troughs they may be filled from the chutes. The said troughs are suitably supported upon the side members of the framing of the machine.

As shown most clearly in Fig. 21, the bottom 66 of each trough is recessed and receives therein a sprocket chain 67 having spaced upstanding lugs 68 arranged in pairs sufficiently separated to receive between 130

them the cartons fed in by the belts 45, 46. As hereinafter set forth, the said sprocket chains are intermittently driven and are so timed that they are periodically stopped 5 with the upstanding lugs 68 so positioned as to receive a carton lengthwise therebetween. The movement of the sprocket chains is then resumed and the cartons are carried into the filling position and then 10 into the closing position.

Each sprocket chain 67 is supported at its outer end by an idler or guide sprocket wheel 69 upon the shaft 69, shown most clearly in Figs. 2 and 5, and having any 15 suitable means to adjust the same, thereby to cause said sprockets to run with sufficient tautness. At its inner end, each sprocket passes about a sprocket wheel 70 fast upon a transversely extending shaft 71 and having thereon a pinion 72 meshing with the teeth 73 of a mutilated gear 74 mounted upon a shaft 75, whereby in each 20 rotation of the said gear 74 each sprocket chain is driven through the proper distance to receive and convey one carton. The shaft 71, as shown most clearly in Fig. 5, extends across the machine and at the opposite end is provided with a sprocket pinion to drive the other sprocket chain 67.

30 I will next describe the parts which coact to fold the upstanding portions of the carton or its lining, and thereafter will set forth in detail the means by which the various parts of the apparatus are operated 35 from the motor or driver.

Referring again to Fig. 24, it will be observed that at the front of the trough, the outer wall of which is cut away at the point where the cartons are received therein, the 40 only portion of the carton extending above the outer wall thereof is the portion 44 of the lining. In this embodiment of the invention said upstanding portion of the lining is the first part to be folded down onto 45 the crackers or other articles which have been deposited in the carton through one of the chutes 16, 17.

In order to fold down the said upstanding portion 44 of the lining, I preferably 50 provide a plate 76 which is supported for sliding movement in a horizontal plane upon a guideway 77 having side or longitudinal members 78, 79 and an outer cross or end member 80, thus providing a longitudinal 55 space 81.

As shown most clearly in Fig. 28, the inner edges of the members 78, 79 are provided with longitudinal grooves for the reception of wedge-like portions 82—82 laterally extending from and integral with the body of a block 83 received in the longitudinal opening 81. The plate 76 is secured by a bolt 84 to the said block 83 and to the latter is pivotally secured at 85 a link 86 65 itself pivotally connected at 87 to a lever

88 pivoted at 89 upon an upstanding portion 90 of a bracket 91 bolted at 92 to an upstanding part of the framing of the machine. A coil spring 93 is connected at one end 94 to the lever 88 and at its opposite 70 end 95 to the block 83. The wedge-like guiding portions 82 of the block have their thin edges inwardly directed, and the construction and arrangement of parts and the connection of the spring 93 to the block 75 are such that the said spring 93 tends, as the plate 76 begins its inward movement, slightly to tilt or rock upwardly the inner edge of said plate 76, so as to guide it safely over the upstanding edge of the carton proper and the outer upstanding edge of the trough. At or near the inner ends of the grooves in the members 78, 79 are provided downwardly directed wedge portions 96 under which the wedges 82, 83 are 80 received in the inward movement of the plate 76, thereby to again rock downwardly the said plate 76 and to insure the proper folding down thereby of the upstanding portion 44 of the lining into the position indicated in Fig. 25.

At a suitable time with respect to the infolding of the upstanding portion 44 of the lining and preferably very shortly thereafter, and in practice substantially simultaneously therewith, I down-turn or infold the upstanding end flaps 39, 40 of the carton and the portions 42 of the lining positioned flatwise thereagainst. This I preferably accomplish through the agency of two 100 levers 97, 98, shown in detail in Figs. 8 and 9, and in part in Figs. 12, 14, 16, 18, 24, 25, 26 and elsewhere. These levers are provided at their outer free ends with spoon-like heads or ends 99, 100, and viewing particularly Fig. 20 it will be observed that the inwardly directed edges 101, 102 thereof are upturned so that in their inward movement upon contact with the upturned flaps, they will ride safely over the body of the carton, 105 as indicated clearly in Fig. 26. As also clearly indicated in Fig. 20, the opposite or outer edge of each of the spoon-like heads 99, 100 is longitudinally enlarged as indicated at 103, so as to provide a longitudinal 110 shoulder 104. In the inward motion of the heads 99, 100, the said shoulders 104 engage the upper edges of the end walls 105 of the body of the carton, thereby holding the ends of the carton in proper relation with respect to each other and also insuring the proper positioning of the now downturned end flaps 39, 40, as indicated in Fig. 26.

The levers 97, 98 are pivotally mounted at 106, 107 upon a cross arm 108 bolted at 125 109 to a block 110 mounted for sliding movement in a horizontal plane upon a guide 111 extending inwardly from the frame and from each trough, as indicated most clearly in Figs. 10 and 11. The outer ends 112 of 130

said levers 97, 98 are connected by a coil spring 113 tending to separate the spoon-like heads 99, 100. The block 110 has a downwardly extending portion 114 having 5 a face to face relation with the side of the guide 111, and thereto is pivoted at 115 a link 116, to the inner end whereof at 117 is pivotally connected a lever 118 itself pivoted at 119 upon the bracket 91. As shown 10 most clearly in Figs. 8 and 9 at or near the inner end of each guide 111, there is bolted or otherwise secured a transversely extending strip 120, the outer ends whereof are perforated for the free passage of the 15 threaded ends 121 of rods 122 pivoted at 123 to rocker arms 124 fast upon the pivots 106, whereby swinging movement is imparted to the levers 97, 98. The outer ends of the rods 122, 123 have stop nuts 125 which 20 may be adjusted to the desired position.

When the parts are in the position shown in Fig. 8 with the levers 97, 98 most widely separated and in their inner positions, the nuts 125 are out of contact with the transverse strip 120, but in the inward movement of the levers 97, 98 upon their supporting block 110, the stop nuts 125 come into contact with the transverse strip 120, as indicated in Fig. 9, with the result that the 25 spoon-like heads are swung into the position shown in Fig. 9, and thus fold down the end flaps 39, 40 and the adjacent upstanding portions of the lining.

The levers 97, 98 and their supporting cross strip 108 may be moved to and fro in any suitable manner, as hereinafter described. Although the same need not be employed, I have herein represented as cooperating in the return or inward movement 30 of said parts a coiled spring 126, the outer end of which is connected at 127 to the transverse strip 108 and the outer end of which is connected at 128 to a rod 129 connected to a post 130 secured to and upstanding 35 from the guide 111.

As shown most clearly in Fig. 17, the cover portion 41 of the carton, which is of the same length as the carton itself, is provided with a free edge portion 131 normally 40 lying in a slightly different plane than the portion 41 of the cover by reason of the fact that the cover is longitudinally creased along substantially the line 132 as indicated in Figs. 17 and 26. I provide suitable means 45 whereby the cover portion 41 and the part of the lining that is upstanding and is positioned thereagainst are folded down onto the now in-folded front portion of the lining and end flaps, and I also provide means for 50 so guiding the edge portion 131 that it is inserted between the lining and the outer upstanding wall 133 of the carton, as indicated in Fig. 19.

Preferably also I provide guiding means 55 whereby the upstanding cover portion is

prevented from getting into a position back of the cover-closing means. For this purpose and as best illustrated in Figs. 5, 21 and 23, I employ a fixed guide 133.

For closing the cover portion 41 and as shown most clearly in Figs. 13, 15, 17, 19 and also in Figs. 10 and 11, I also mount for to and fro sliding movement in a horizontal plane upon the guide 111 a block 134 having a downwardly extending portion 135 guided 75 along the vertical side of the guide 111 opposite to the downwardly extending portion 114 of the sliding block 110. To said downwardly extending portion 135 is pivotally connected at 136 a lever 137 itself pivoted at 119 to the bracket 91 previously described.

Upstanding from the sliding block 131 are two posts 138 suitably connected to a cross member of which at 139 is a coil spring 140, the outer end of which is connected at 141 85 to the post or bracket 130 previously referred to. The said spring 140 tends to move the block 134 with its posts 138 and other parts inwardly or to the right, viewing Figs. 10 and 11, and therefore to swing the cover-closing means into upright position, as shown in said figures. Pivotally connected at 143 to the upper end of the posts 138 are two parallel links 144, the outer ends of which are pivotally connected at 145 to enlargements or lugs upon the cover-closing member 146. Said cover-closing member is pivoted at 147 at the upper inner edge of the inner upstanding wall of the trough and is adapted to be folded down into horizontal 90 position. Preferably I form the cover-closing member 146 with a supplemental portion 148 normally outwardly spring pressed in any suitable manner, as by two coil springs 149, each surrounding a screw 100 or bolt 150, the upper end of which is connected at 151 to said member 148 and the lower end of which is threaded at 152 and is adjustably received in a tapped lug 153 extending from the body of the cover-closing 105 member. I have herein represented the body portion 146 of the cover-closing member as having a guiding extension 154 along which the supplemental portion may slide, as clearly indicated in Figs. 13 and 15.

In order to guide the free edge portion 131 of the cover into proper position and suitably to fold the same for its insertion between the body of the carton and the lining, I may provide any suitable means. Herein for the purpose I have provided an arch-like member 155 pivoted at 156 upon a vertical rod 157, itself mounted for vertical sliding movement in the upright portion of the machine frame. To the outer edge of the arch member 155 is connected at 158 a coil spring 159, the upper end of the latter being connected at 160 to the said vertically positioned slide 157. The inner edge of the arch member 155 has flexibly connected thereto at 125 165

161 a flexible member herein represented as a chain 162, the upper end of which is connected at 163 to a terminal screw or pin 164 loosely received within a suitable socket 165.

5 The construction and relation of parts are such that as the arch member 155 is moved downward with the slide 157 by means hereinafter described, the chain 162 being fixedly connected at its upper end elevates the inner 10 edge of said arch member 155, and therefore depresses the outer edge of said arch member against the tension of the spring 159 and into the position indicated in Figs. 17 and 19.

For the sake of clearness, the spring 159 15 and chain 162 have been omitted from Figs. 13, 15, 17, 19.

When the arched member 155 has been moved into the position shown in Figs. 17 20 and 19, the supplemental portion 148 of the cover-closing member 146 is guided along the inner face thereof, the springs 149 yielding for this purpose, and thereby the free edge 131 is guided into position between the front wall of the lining, and the front wall 25 of the body 133 of the carton, as clearly shown in Fig. 19.

The timing of the parts is such that the several parts which have been described for closing upstanding portions of the carton 30 act in very rapid succession and almost simultaneously. After the carton has been closed and the sprocket chain supporting the same is again moved onwardly, the outer edge of the closed carton passes beneath the 35 overhanging guide or ledge 166, clearly shown in Figs. 5, 24, 25 and 26. In order to prevent the self opening of the carton after closure, I preferably provide means whereby I augment the longitudinal crease 40 at the base of the cover of the carton; that is, I further crease the same along the meeting line of the inner upstanding wall of the carton and the cover portion thereof. This I preferably effect by passing the closed carton beneath the disk 167, shown most clearly 45 in Figs. 3 and 5, and as mounted upon a horizontal pivot and having a hub portion 168 so positioned as to bear with creasing force upon the now closed cover of the carton. The said disk 167 has its body portion 50 169 so positioned that it enters between the inner wall of the carton and the adjacent upstanding wall of the trough, the disk being preferably somewhat sharpened for this 55 purpose.

Viewing Fig. 5, it will be observed that the guide 166 is opposite said disk 167, the result being that the front or outer side of the carton or receptacle is held down while 60 the said disk is acting to crease or make more pronounced the crease along the line of junction of the cover and body of the carton.

Preferably though not necessarily I im- 65 part a shaking or jarring action to the car-

ton after the same has been filled or as it is being filled and prior to the closing thereof. For this purpose, I may provide any suitable means but preferably, as shown in Figs. 21 and 23, I provide a U-shaped member 170, 70 the upstanding portions 171, 172 of which enter between the upstanding walls of the trough and the body of the carton directly beneath the mouth of the co-acting chute 16 or 17. The said shaking or jarring member 75 may be operated in any suitable manner, and for this purpose I have represented it as secured by screws 173 to the squared portion of the rock shaft 174, the rounded end portions 175 of which are mounted in suitable bearings 176 at the under side of the trough. To one of said portions is suitably connected a link 177 pivotally connected at 178 to an operating rod 179. The cartons may be discharged from the two sides of the machine 80 in any suitable manner and to any desired point. I have herein represented in Fig. 2, a duplex discharge chute 180 hinged to the frame of the machine at 181, 182, so that when the machine is not in use, the chute can 85 be folded up out of the way. The two parts 183, 184 of the chute meet at 185 and from this point the filled and closed receptacles are discharged.

In order to drive the various operating 90 parts of the machine, I may provide any suitable means. In Fig. 5 and elsewhere, I have represented the preferred form of means employed by me. Any suitable motive power may be employed. Preferably, 100 as indicated in said figure, I employ an electric motor 186 of any suitable type and controlled by switching means generally indicated at 187. Passing about the shaft 188 of the electric motor is a belt 189 also passing 105 about a pulley 190 loosely mounted upon a transverse shaft 191 mounted in suitable bearings 192—192 upon the framing of the machine. The said pulley 190 is adapted to be clutched to the shaft by any suitable 110 clutching means and herein is represented as having an annularly grooved member 193 receiving the inner end of an operating yoke 194 inwardly extending from a rod 195 extending from side to side of the machine and 115 guided in the side members thereof, as indicated in said Fig. 5. The ends of the said slide rod are provided with teeth 196—196 meshing with pinions 197—197 upon vertically extending shafts 198, one of which is 120 shown in Fig. 1 as mounted in suitable bearings in the framing of the machine. At the upper end of each of said shafts 198 is a bevelled pinion 199 meshing with a similar pinion 200 upon the end of a starting and stop- 125 ping rod 201, itself mounted for rocking movement in suitable bearings 202 and preferably extending nearly the entire length of the machine. The said starting and stop- ping rod is provided with a series of suit- 130

ably spaced handles 203, so that the attendant at either side of the machine and at several points along the length thereof may start and stop the machine. The main drive shaft 191 is provided with a pinion 204 fast thereon and meshing with a gear 205 fast upon a transversely extending shaft 206 mounted in bearings 207 in side members of the machine frame. Fast upon said shaft 206 and about mid-width of the machine is a beveled gear 208 meshing with a similar gear 209 upon the longitudinally extending shaft 52 whereon is supported the pulley 50 for the empty carton feeding belt 46.

15 As previously stated, I preferably intermittently drive the empty carton conveyer belts 46. For this purpose, I have represented the shaft 52 as having thereon a clutch member 210 by which periodically to 20 clutch to the shaft the gear 56 preferably loosely mounted thereon. In order to operate the clutch 210, I provide a clutch operating member 211 pivoted at 212 upon the framing of the machine and having a laterally extending arm 213, to which is connected a lever arm 214 having a roll 215 normally in engagement with the periphery of the cam 216 upon the cam shaft 217. The lever arm 214 is pivotally mounted upon a stationary support 218, as most clearly indicated in Fig. 6, and extends both above and below the same, it being pivotally connected at its lower end at 219 to the said laterally extending arm 213 of the clutch operating 30 member. At certain times, it is desirable to stop the belts 45, 46 without stopping the other parts of the machine, and I have provided means whereby this may be effected. As shown most clearly in Fig. 6, I provide a 35 link 220, the lower end of which is pivoted at 221 to the said lever arm 214 adjacent to the upper end thereof. The said link extends in an upwardly inclined direction to a side of the machine adjacent to one of the 40 discharge chutes and is there suitably supported by a pin upon a downwardly extending bracket 222 entering a longitudinal slot 223 in said link, whereby said link may be outwardly drawn by the handle 224 so as to 45 withdraw the roll 215 from operative relation to the periphery of the cam 216. When the roll 215 has thus been withdrawn, the movements of the belts 45, 46 are entirely suspended.

50 The carton-closing means and other parts of the machine may be operated in any suitable manner, but preferably I operate them to certain of them, by cams upon the cam shaft 217. Such cams may be of any suitable type, but with the exception of the cam 55 216, they are herein represented as track cams.

Viewing Fig. 5 and also Figs. 8, 9, 10, 11, it will be observed that upon the cam shaft 217 are mounted five cams respec-

tively numbered 225, 226, 227, 228, 216, reading from the right in Fig. 5. The cam 225 operates the end flap-closing members, and for this purpose, as shown most clearly in Figs. 8, 9, 10, 11, it is provided with a cam 70 groove 229 to receive a roll 230 mounted upon the upper end of a lever arm 231 loosely pivoted upon a stationary shaft 232. Pivoted to the lever arm 231 at its upper end at 233 is a link 234. The opposite 75 end of said link 234 is pivotally connected at 235 to the lever arm 118, whereby in the rotation of the cam shaft the block 110 together with the adjacent end flap-closing levers 97, 98 are reciprocated as described, 80 and by suitable connections the similar levers on the other side of the machine are operated.

The second cam 226 operates the sliding plates 76, whereby the upstanding front 85 wall of the carton lining is folded. This cam is provided with a camway, not herein shown, to receive a cam roll 236 upon the upper end of a lever arm 237 pivoted upon the said stationary shaft 232 and extending 90 below the same, as indicated at 238 in said figures. To the said lower end 238 of the lever 237 are pivotally connected at 239 two links 240, 241 extending to the two plates 76 at opposite sides of the machine, whereby in the rotation of the said cam 236 both 95 of said plates are moved in unison.

The third cam 227 operates the cover-closing members 146 and to that end it is provided with a cam track to receive a cam 100 roll 242 pivotally mounted upon an arm 243, itself loosely pivoted upon the said stationary shaft 232. From the said shaft extend in opposite directions the links 244, 245 to the opposite sides of the machine, 105 where they are respectively connected to the slide blocks 134. By the described connections, the said slide blocks are moved to and fro in unison, so as to operate the cover-closing members 146 as hereinbefore described.

The fourth cam 228 operates the opening and closing means for the chutes 16, 17. For that purpose the said cam is provided with a track and adapted to receive a cam 115 roll indicated at 246 in Fig. 5. The said cam roll is mounted upon an arm 247, shown most clearly in Fig. 7, the said lever arm being loosely pivoted upon the said stationary shaft 218. Connected to the said lever 120 arm 247 above and below its pivotal point are links 248, 249, which extend to the opposite side of the machine and there are pivotally connected by pins 250—250 to crank arms 251 having therein slots 252. 125 The said crank arms are fast upon the shafts 253 mounted in suitable bearings and having fast thereon mutilated gears 254, the teeth whereof mesh with the teeth 255 of links 256 which extend upward and are piv- 130

oted at 257 to levers 258, themselves pivoted at 259 upon brackets 260 depending from longitudinally extending members of the machine frame. To the outer ends of said 5 levers 258 are pivotally connected at 261 links 262 fast to the pivots 263 of the fingers 33 of the chute closing members, as most clearly indicated in Fig. 22.

Thus, in the rotation of the said cam 228, 10 the fingers 33 are moved into closing and open position. Upon the outer ends of the levers 258, I have also pivotally connected at 261 arms 264 which, in the opening movement of the fingers 33, are adapted to strike 15 rolls 265 upon the supporting arms for the fingers 34, and thereby to depress said fingers, the rolls 265 being eccentric to the pivots 36 for said fingers.

Viewing Fig. 6, it will be evident that in 20 the opening movement of the set of fingers 33, 34, the fingers 33 open somewhat in advance of the fingers 34. While I am not limited to such action of parts, the same is 25 advantageous in that the fingers 33 in their initial movement press back the upstanding portion of the cover substantially as indicated in dotted lines in Fig. 21, so as to insure a free passage for the discharging crackers. At the front of the carton, 30 the lining does not extend as high as the cover, and hence there is less liability of such lining assuming an obstructing position at the front of the carton.

I have stated that the arch guide 155 35 for the cover-closing member is carried by a vertical slide 157.

As shown most clearly in Figs. 1, 3 and 7, the said vertical slide 157 has at its upper end a pin 266 that is received in a longitudinal slot 267 in an arm 268 of a lever 269 pivoted at 270 in suitable bearings upon the framing of the machine and having a downwardly extending arm 271, to which is pivotally connected at 272 a link 273 pivotally connected at 274 to a lever 275 pivoted at 276 on the framing of the machine and having a roll 277 which engages a track 278 in a cam 279 fast upon the shaft 74. The shape of the track 278 is such that the 50 slide 157 is lowered at the proper time to guide the free edge of the cover into position.

Any suitable means may be employed to operate the shakers 170 positioned in 55 troughs 62, 63. Herein for the purpose I have in Fig. 5 represented each of the rods 179 extending from the said shakers as connected to an eccentric strap 280 shown in Fig. 5 surrounding an eccentric 281 upon 60 the end of a short shaft 282 mounted in bearings 283 upon the machine frame and having a pinion 284 meshing with a gear 285 fast upon the belt driving shaft 252. In this manner, an intermittent shaking movement is imparted to said shakers. Any suit-

able means may be employed to rotate the brush 11 that is positioned above the distributing disk-like member 8. Herein for the purpose I have represented said brush as mounted upon a shaft 286 shown most 70 clearly in Figs. 4 and 6, and having a pulley 287 driven by a belt 288, which, as shown in Figs. 3 and 5, passes about a pulley 289 upon the shaft 206. A suitable guide pulley 290 may be employed if desired. In the described manner, the brush shaft is constantly rotated.

Any suitable means may be provided to drive the apron 4 for conveying the loose crackers to the disk member 8. I have herein represented, as shown most clearly in Figs. 3 and 7, the pulley 6 as fast upon a shaft 291 and a shaft 294 having thereon a sprocket gear 295 driven by a sprocket chain 296 passing about a suitable sprocket 85 gear upon the shaft 279. In this manner, the said apron 4 is continuously driven in the direction of the arrow adjacent thereto in Fig. 7.

In the disclosed embodiment of my invention, the timing of the parts is such that the plate 76 acts first to fold in the upstanding front portion of the lining. While the said plate is in its inward position, as represented in Fig. 25, the end flap-closing devices 97, 98 sweep inwardly and fold the end flaps down onto the plate 76. The movement of the levers 97, 98 is extremely rapid. The arched guide device 155 starts on its downward movement substantially as the levers 100 97, 98 commence to move outwardly, and it as stated serves as a guide for the main cover portion of the carton, so that the bent or deflected front edge of the main cover portion is guided between the front 105 wall of the carton and the paper lining. I am not, however, limited to the timing herein described, as any suitable timing may be employed that will insure the proper folding of the several parts into closed position. 110

It is clear from the foregoing description that in the disclosed embodiment of my invention, wherein a duplex machine is illustrated, the empty cartons are intermittently fed at each side of the machine into the 115 troughs where they are received upon the sprocket chains in suitable spaced relation. While the cartons are securely held in position the crackers are discharged through the chutes 16, 17 at opposite sides 120 of the machine into the cartons which preferably are shaken as the crackers are discharged thereinto. Immediately thereafter the filled cartons are advanced and the end flaps and cover together with the upstanding portions of the lining are folded down into closed position. The cartons then pass beneath means which so crease or act upon the cover as to prevent the cover springing into open or partially open position. There- 125 130

after the cartons are discharged from the machine and may be further handled in any suitable manner.

So far as I am aware, I am the first to provide mechanism automatically to fill cartons with oyster crackers and to close the cartons, and I desire to claim my invention commensurate with the breadth thereof.

Having thus described one illustrative embodiment of my invention, I desire it to be understood that although specific terms are employed, they are used in a generic and descriptive sense and not for purposes of limitation, the scope of the invention being set forth in the following claims.

Claims:

1. Means for filling receptacles with divided solid material comprising in combination, receptacle feeding means, means for depositing the material in the receptacles, and automatically acting means for moving into closed position the cover portions of said receptacles and for tucking in said portions, including horizontally movable means operable from one side of said receptacle, a pair of horizontally swinging, simultaneously operable arms operating substantially at right angles to the first-mentioned means and a vertically swinging member to operate from the remaining side of said receptacle.

2. A receptacle-filling apparatus comprising in combination, traveling means to feed empty cartons or receptacles, an endless conveyer onto which the latter are fed directly from and by said traveling means, said conveyer being angularly positioned with respect to said traveling means, means to fill said cartons or receptacles while on said conveyer, and means to close said filled cartons or receptacles, said traveling means and conveyer being arranged to support said cartons or receptacles throughout with their openings upward.

3. Receptacle filling means comprising in combination, two endless belts at right angles to each other and adapted one to convey receptacles automatically to the other, and means to fill and close the receptacles while upon the second belt, said filling means having parts to engage the receptacles and hold them in open position, and said closing means including parts to fold down a lining and three flaps.

4. Receptacle filling means comprising in combination, two endless belts at right angles to each other and adapted one to convey receptacles automatically to the other, and means to fill and automatically to close the receptacles while upon the second belt.

5. Means for filling cartons or receptacles with divided solid material comprising a horizontal belt to support said cartons or receptacles, means to fill the latter while on said belt, means to embrace the cartons or

receptacles while on the belt and to shake the cartons or receptacles to settle down the contents thereof and means to close said cartons or receptacles.

6. Means for filling cartons or receptacles with divided solid material comprising a horizontal endless conveyer to support a carton or receptacle, a filling device, forked means positioned beneath the filling device to embrace and to shake said carton or receptacle while it is on the conveyer in filling position and means to close said filled, shaken carton or receptacle.

7. A receptacle filling apparatus comprising, in combination, forwardly traveling means to feed cartons or receptacles, an endless conveyer on to which the latter are fed directly from and by said traveling means, said conveyer being angularly positioned with respect to said traveling means, means to fill said cartons or receptacles while on said conveyer, and means to close said filled cartons or receptacles.

8. Means to fill cartons or receptacles having an upstanding end flap, means to turn said flap into closed position after the filling operation and means to superpose another flap thereon and to tuck in said superposed flap including a vertically movable arched guide.

9. Means for supporting a carton or receptacle having upstanding end flaps, pivoted closure members co-acting therewith, means to swing said members upon their pivots including a fixed member, rods connected with said closure members and adjustable stops on said rods, and means to impart bodily movement to said members in the plane in which they are swung.

10. Means to support a carton having when open upstanding flaps, opposed closure levers therefor, means to swing said levers including a stationary member, rods connected with said levers to move therewith and adjustable abutments on said rods to engage said stationary member, and a slide whereon said levers are mounted for to and fro movement in the plane in which they are swung.

11. Means to support a carton or receptacle having when open upstanding flaps, opposed closure members therefor, and means to impart a combined swinging and bodily movement to said members in the same plane including a stationary member, rods pivotally connected with said closure members and slidable in said stationary member and adjustable abutments on said rods to engage said stationary member.

12. A conveyer to receive a carton or receptacle having when open upstanding lining portions, a plate supported in parallelism to the face of the conveyer but spaced therefrom a distance substantially equaling the height of the carton or receptacle, means

to impart to and fro movement to said plate to fold an upstanding portion of the lining onto the contents of the carton or receptacle, a lever to operate said plate, means to effect 5 an upward and a subsequent downward movement to the forward edge of said plate during the folding operation thereof, means acting subsequently to fold down simultaneously both ends of the carton cover, and 10 means opposite to said plate to fold down the remaining portion of the carton cover.

13. A carton or receptacle filling apparatus comprising, in combination, a traveling conveyer, a trough in which the same is 15 positioned, and means co-acting with the carton or receptacle while in the trough upon the conveyer to close the cover portions thereof and including means to fold down a lining portion, subsequently acting means 20 to fold down simultaneously both end portions of the cover, and means acting thereafter to fold down the remaining cover portion.

14. Carton or receptacle filling and closing means comprising in combination, a traveling conveyer, a trough in which the same travels, means to fill the carton or receptacle while on the conveyer in the trough, and means automatically to close the cover portions 30 of the carton or receptacle after filling and while in said trough and including means to fold down a lining portion, subsequently acting means to fold down simultaneously both end portions of the cover, 35 and means acting thereafter to fold down the remaining cover portion.

15. Carton and receptacle filling and closing means comprising in combination, a traveling conveyer constituting a support 40 for a carton or receptacle having when open upstanding end flaps and a cover, a trough in which said conveyer travels, means to fill the carton or receptacle while in said trough on the conveyer, swinging means positioned at the upper edge of the trough 45 movable in a horizontal plane to close said end flaps and means to fold down the cover and tuck in the front edge thereof.

16. Carton and receptacle filling and closing means comprising in combination, a traveling conveyer to support a carton or receptacle having upstanding end flaps and a longitudinally extending main cover, means to fill the carton or receptacle while 55 on the conveyer in the trough, swinging means positioned at the upper edge of the trough and movable in a horizontal plane to fold said end flaps and means mounted to swing in a vertical plane to fold down 60 the main cover portion onto the contents of the carton or receptacle and to tuck in the front edge thereof.

17. Receptacle filling means comprising in combination, two endless belts at right

angles to each other and adapted one to 65 convey receptacles automatically to the other, said belts each having horizontal runs whereon the receptacles are supported, means to deflect the receptacle-supporting run of one of said belts beneath that of said 70 other belt, and means to fill and automatically to close the receptacles while upon the horizontal run of the second belt.

18. Means including a traveling member having a horizontal run to support upright 75 a carton or receptacle having when open upstanding flaps, opposed closure members for said flaps, yieldable separating means for said closure members and means to impart a combined swinging and bodily movement to 80 said closure members while the carton or receptacle is supported upon the said horizontal run to effect a positive closing movement of said closure members.

19. Carton filling and closing means comprising in combination, a traveling conveyer to support a carton or receptacle having when open a longitudinally extending, upstanding cover portion and upstanding end portions, means to fill said carton or receptacle, means to fold down said end portions, means to fold said cover portion and means to tuck in the front edge of said cover portion, a removable arched guiding member and a swinging member to coöperate with 95 said arched guiding member.

20. Carton filling and closing means comprising in combination, a conveyer to support a carton or receptacle having, when open, a longitudinally extending, upstanding cover portion having a bent or deflected front edge, means to fill the carton, means to close said cover onto the contents thereof, and periodically positioned, arched means to guide or position the bent or deflected front edge of said cover during the closing movement of the cover, so that the cover is closed and its edge tucked in, in a single operation.

21. Carton or receptacle filling and closing means comprising in combination, a traveling conveyer to support a carton having a longitudinally extending, upstanding cover portion with a bent or deflected front edge, means to fill the carton, means to fold 110 said cover portion onto the contents thereof, means to guide said bent or deflected front edge into position between an upstanding wall of the carton and the contents thereof, and means periodically to position said 115 guiding means in guiding relation, including a flexible member attached to one portion of said guiding means and a spring to oppose said flexible member.

22. Carton filling and closing means comprising in combination, means to support a carton having a cover portion provided with a bent or deflected front edge and upstand

- ing end portions, means to fill the carton, headed levers mounted to swing in a horizontal plane and thereby simultaneously to fold in both end portions, means to fold 5 said cover portion onto the contents thereof, and means to guide said bent or deflected front edge into position between the upstanding wall of the carton and the contents thereof.
- 10 23. Means to fill and close a carton or receptacle comprising in combination, supporting means for a carton having a lining and a folding cover provided with a bent or deflected front edge, means to fill the carton 15 or receptacle, means to fold the cover portion onto the contents, and means to guide the bent or deflected edge into position between an upstanding wall of the carton or receptacle and the lining thereof during the 20 folding movement of the cover portion, including a normally retracted, cam-actuated, arched guide member.
24. Carton filling and closing means comprising in combination, means to support a 25 carton having upstanding end flaps and a longitudinally extending, main cover portion, means to fill the carton, subsequently acting means to fold in the end flaps including normally withdrawn folders, a support 30 upon which said folders are pivotally mounted, means to move said support and said folders bodily toward the carton to be folded, a relatively fixed member to impart swinging movement to said folders at pre- 35 determined points in the bodily movement of said support and means operating thereafter to fold the main cover portion down thereonto.
25. Carton filling and closing means comprising in combination, means to support a 40 carton with an upstanding, separate lining, upstanding end flaps, and a longitudinally extending, main cover portion, means to fill the carton and subsequently acting means to fold down the front upstanding portion of 45 the lining, means including levers mounted to swing in a horizontal plane, to fold down the end flaps onto said lining portion, and means to fold the main cover portion down 50 onto the said folded end flaps with the edge of the main cover portion inserted between the contents of the carton and the front wall thereof.
26. Traveling means to support a carton 55 having an upstanding cover portion integral with the body, means to fill the carton, means to fold said cover onto the contents thereof, and a rotary disk having a relatively sharp edge and a hub, said hub being 60 positioned to bear upon the closed cover near the line of junction thereof with the body.
27. Means to support a carton having an upstanding cover portion integral with the 65 body, said cover portion having a bent or deflected front edge, an arch shaped guide for said front edge, means to move said guide into and out of active position, and co-acting means to fold the cover portion onto the carton. 70
28. A conveyer to receive a carton or receptacle having when open upstanding lining portions, a plate supported in parallelism to the face of the conveyer but spaced therefrom a distance equaling the height of 75 the carton or receptacle, means to impart to and fro movement to said plate to fold an upstanding portion of the lining onto the contents of the carton or receptacle, means opposite to said plate to fold down 80 a carton cover portion, and means co-acting therewith to tuck in an edge of such cover portion.
29. An apparatus for filling and closing 85 cartons comprising in combination, a movable conveyer to support a carton having when open upstanding cover members, distributing means for filling the cartons, closures for said filling means, means to fold down an upstanding lining portion for 90 the carton, means mounted for swinging and bodily movement in a horizontal plane to fold down upstanding end flaps thereof, means to fold down a main cover portion 95 thereof, a cam shaft, cams thereon, and connections from said cams to said several means to operate said parts.
30. A duplex machine for filling and closing cartons comprising in combination, 100 a conveyer at opposite sides of the machine to support cartons having upstanding lining portions, end flaps, and main cover portions, means to fold down each of said portions including means swinging in a horizontal plane to fold down simultaneously 105 both end flaps, a single cam shaft, cams thereon, and connections from each cam shaft to both sides of the machine to operate said several means.
31. A carton filling machine having a 110 conveyer belt adapted to receive empty cartons and to convey them inwardly, a second conveyer belt onto which the cartons are discharged from the first belt, said second belt being positioned at an angle to the first belt and said first belt extending to and then beneath said second belt, whereby the cartons are discharged directly from the first onto the second belt, means to fill the cartons while on said second belt, and means to close 115 the filled cartons.
32. A carton filling machine comprising in combination, a conveyer belt adapted to receive empty cartons and to convey them inwardly, a second conveyer belt arranged 120 at substantially right angles thereto, said first belt extending substantially to and then abruptly beneath the second belt, one 125

or more guides adjacent to said first belt to convey cartons directly therefrom onto the second belt, means to fill the cartons while on said second belt, and means to close 5 the filled cartons.

33. A carton filling device comprising in combination a conveyer belt adapted to receive empty cartons and to convey them inwardly, means to impart step-by-step motion to said belt, a second belt positioned at 10 an angle to the first belt and adapted to receive the cartons directly therefrom, and means to impart step-by-step movement to said second belt, means to fill the cartons 15 while on said second belt, and means to close the filled cartons.

34. A carton filling device having a conveyer belt adapted to receive empty cartons and to convey them inwardly, means to impart a step-by-step motion to said belt, a second belt arranged at substantially right angles to the first belt, means to impart movement to said second belt during the 20 periods of rest of said first belt, means to 25 fill the cartons while on said second belt, and means to close the filled cartons.

35. A carton filling machine comprising in combination, a conveyer belt adapted to receive empty cartons and to move them inwardly, means to impart a step-by-step motion thereto, a second conveyer belt arranged transversely to the first belt and having spaced carton-receiving projections thereon, means intermittently to move said second 30 conveyer belt into stationary position to receive cartons from the first belt, means to fill the cartons while on said second belt, and means to close the filled cartons.

36. A carton filling machine comprising 40 in combination, a conveyer belt adapted to receive empty cartons and move them inwardly, means to impart a step-by-step motion to said belt, a second conveyer belt arranged transversely to said first belt and 45 having spaced carton-positioning projections, means to move said second belt during the periods of rest of said first belt into position to receive cartons between said projections from the first belt, means to fill the cartons while on said second belt, and means to 50 close the filled cartons.

37. A carton filling and closing machine comprising in combination, a conveyer, a trough in which the same is adapted to 55 travel and to receive a carton having upstanding lining and cover portions, a lining closure at one side of the trough, a main cover closure at the other side thereof, and end flaps closures positioned to sweep in 60 simultaneously at the ends of the carton and prior to movement of said conveyer.

38. A carton filling and closing machine comprising in combination, means to sup-

port a carton with an upstanding lining portion, a plate to fold down said upstanding 65 lining portion means to effect an upward yielding movement of the forward edge of said plate as the plate moves toward the carton thereby to guide it above the upstanding edge the carton, and means for effecting a 70 return downward movement thereof.

39. A carton filling and closing machine comprising in combination, means to support a carton with an upstanding cover portion, a guide for the edge of the cover, and 75 a member to fold down said cover, said member having a yielding part movable along said guide.

40. Means to support a carton having two upstanding end portions and an upstanding cover portion with a bent or deflected edge, means to impart a single movement to said cover portion onto the body, a guide for said edge, means to move said guide into and out of active position, means coöperating 80 with said guide to tuck in said edge as an uninterrupted part of said single movement of the cover, and coöperating means simultaneously to fold in said two upstanding 85 end portions.

41. Means to support a carton having two upstanding end portions, an upstanding cover portion with a bent or deflected edge, and an upstanding lining portion, means to 90 impart a single movement to said cover portion onto the body, a guide for said edge, and means to fold down the lining, the upstanding end portions and the upstanding cover portion and including means to move said guide into and out of active position, 95 and means coöperating with said guide to tuck in said edge as an uninterrupted part 100 of said single movement of the cover.

42. A carton filling and closing machine having means to support a carton with upstanding end flaps and opposed lever arms adapted to swing to and fro and to move bodily in a horizontal plane to engage said end flaps and to simultaneously fold the same down onto the carton, said lever arms having shouldered portion 104.

43. A carton filling and closing machine having means to support a carton with upstanding end flaps, and an upstanding cover portion, opposed lever arms adapted to be swung to and fro and to move bodily in a horizontal plane to simultaneously engage said end flaps and to fold the same down onto the carton, said lever arms having shouldered portions 104, and means to engage said upstanding cover portion and to move the same into closed position.

In testimony whereof, I have signed my name to this specification.

EDWARD E. LAWRENCE.
